UNITED STATES PATENT OFFICE.

EDGAR F. HATHAWAY, OF HORNELLSVILLE, NEW YORK.

DESIGN FOR A FENCE-STRAND.

SPECIFICATION forming part of Design No. 22,350, dated April 11, 1893.

Application filed December 19, 1890. Serial No. 375,212. Term of patent 14 years.

To all whom it may concern:

Be it known that I, EDGAR F. HATHAWAY, a citizen of the United States, residing at Hornellsville, in the county of Steuben and State of New York, have invented and produced a new and original Design for a Fence-Strand, of which the following is a specification.

This design has for its object to provide a novel, attractive, handsome and ornamental fence-strand, and the leading features thereof consist of upper and lower spirally twisted lines, and lines each of which extends across the upper set of spirally twisted lines, then diverges and forms curved bends near the median line between the upper and lower spirally twisted lines and then extends rectilinearly to and across the lower spirally twisted lines.

The design is illustrated by the accompanying drawing, in which the figure is a plan view of a portion of the fence strand.

In the drawing, the numerals 1 and 2, indi-

cate the upper spirally twisted lines and 3 and 4, the lower spirally twisted lines. The numeral 5 indicates the lines which extend 25 across the upper spirally twisted lines each of such lines 5 diverging and formed with curved bends 6, near the median line between the upper and lower spirally twisted lines and then extending rectilinearly to and across the 30 lower spirally twisted lines, as indicated by the numeral 7. This peculiar formation provides a novel and ornamental fence-strand which is very attractive.

What I claim is—

The design for a fence-strand as shown and described.

In testimony whereof I have hereunto set my hand and affixed my seal in presence of two subscribing witnesses.

EDGAR F. HATHAWAY. [L. S.]
